(57) **CLAIM**

The ornamental design for a LED strip with flexible support, as shown and described.

DESCRIPTION

FIG. 1 is a perspective view of the LED strip with flexible support;

FIG. 2 is a front view of the LED strip with flexible support of FIG. 1;

FIG. 3 is a rear view of the LED strip with flexible support of FIG. 1;

FIG. 4 is an end view of the of the LED strip with flexible support of FIG. 1;

FIG. 5 is a top view of the LED strip with flexible support of FIG. 1; and,

FIG. 6 is a bottom view of the LED strip with support of FIG. 1.

The broken lines in the drawing are for illustrative purposes only and form no part of the claimed design.
